United States Patent Office

Des. 213,321

Patented Feb. 18, 1969

213,321

TABLE

Robert E. Kjer Jakobsen, Compton, Calif., assignor to Schlumberger Limited (Schlumberger N.V.), New York, N.Y., a corporation of the Netherlands Antilles

Filed Dec. 29, 1967, Ser. No. 9,975

Term of patent 14 years

U.S. Cl. D33—14

Int. Cl. D6—01

The single view shown in the drawing is an isometrical view of a table embodying my design.

The dominant feature of my design resides in that portion shown in full lines on the drawing.

I claim:

The ornamental design for a table, substantially as shown and described.
